UNITED STATES PATENT OFFICE.

JAMES W. BEST, OF WESTFIELD, ILLINOIS.

FENCE-POST.

1,172,577.

Specification of Letters Patent. Patented Feb. 22, 1916.

Application filed August 28, 1915. Serial No. 47,800.

To all whom it may concern:

Be it known that I, JAMES W. BEST, a citizen of the United States, residing at Westfield, in the county of Clark and State of Illinois, have invented certain new and useful Improvements in Fence-Posts, of which the following is a specification, reference being had to the accompanying drawings.

My invention relates to fence posts, and particularly to means for supporting fence wires thereon.

An object of the invention is the provision of means for supporting and locking the fence wire to fence posts, which means should be very simple and shall positively hold the wires in place.

A further object of my invention is the provision of a reinforcing member particularly adapted to reinforcing concrete posts or posts of like material, which reinforcing member is so formed as to provide for supporting the wires against the face of the post and locking these wires in place.

A further object of my invention is to so construct this reinforcing and wire supporting member that it shall be interlocked with the concrete of the post so that it cannot get out of place.

Other objects will appear in the course of the following description.

My invention is illustrated in the accompanying drawings, wherein:

Figure 1 is a face view of a post constructed in accordance with my invention; Fig. 2 is a fragmentary vertical section of the upper portion of the post shown in Fig. 1, showing my reinforcing plate in elevation; Fig. 3 is a vertical section on the line 3-3 of Fig. 2.

As illustrated in the drawings, 2 designates a concrete post or a post made of other like material in which there is embedded a reinforcing member designated generally 3. This reinforcing member consists of a strip 45 of metal or other suitable material having a thickness in practice of about one-third of an inch, this strip of metal being embedded in the post and extending vertically therethrough. The strip has such dimensions as 50 to be embedded to a relatively great depth within the post and is locked therein by forming the strip with the openings 4, these openings being filled by the material of the post and thus the strip interlocked firmly 55 with the post. I do not wish to limit myself to the particular form of the openings 4

illustrated as it is obvious that this form may be changed, but preferably these openings are elliptical or elongated apertures.

The edge of the strip beyond the post is 60 formed as illustrated at the lower end of Fig. 2 with an inwardly extending slot 5 intersecting a vertical slot 6. This vertical slot 6 adjacent its lower end is intersected by a fence wire seat 7. The fence wires 8 are 65 disposed within the seats 7 as illustrated in Fig. 2, and held from outward movement through the entrance slots 5 by the construction shown in Figs. 2 and 3. In Figs. 2 and 3 elliptical locking members 9 are used which 70 are forced transversely through the slots 6. In the upper part of Fig. 3 this elliptical member 9 is shown as tapering from one end to the other so that it may be readily inserted in the slot 5 and driven home. Now 75 if it is desired to operatively lock this elliptical locking member in place, the small end of the locking member is expanded as shown in the lower end of Fig. 3 so that the locking member cannot be withdrawn unless this locking member be compressed. The locking member when inserted in these slots 6 extends across the wires 8 and prevents these wires from leaving the seats 7 and being pulled out through the entrance slots 5. 80

I wish it understood that my invention is not limited to the use of a plate 3 embedded in the fence post, as this plate 3 might be formed integral with the fence post if the latter were formed of metal. Neither do I 90 wish to limit myself to the exact details of construction illustrated as these details might be varied without departing from the spirit of my invention. If the member 3 is formed integral with the fence post, as by 95 casting, as above described, this plate 3 will have the form of a web projecting from the face of the post. I have, therefore, used this term "web" in certain of the claims herein-after presented as a term including not only a web or plate embedded in a post of different material but also as including such a web projecting outward from the face of the post and cast with the body of the post. 100

Having thus described my invention, what I claim is:

1. The combination with a concrete post, of a web embedded within the post, said web projecting beyond the face of the post and this projecting margin of the web being 110 formed with a plurality of inwardly extending slots, a plurality of vertical slots each in-

- intersected by the inwardly extending slots and a plurality of wire seats each intersecting the rear wall of one of the vertical slots below the inwardly extending slot, and continuous loops formed of a bendable strand of material whereby a portion of said loops may be expanded, adapted to be inserted through the vertical slots and acting to lock the fence wire within each of the seats.
10. 2. The combination with a concrete post, of a web embedded within the post, said web projecting beyond the face of the post and this projecting margin of the web being formed with a plurality of inwardly extending slots, a plurality of vertical slots each intersected by the inwardly extending slots

and a plurality of wire seats each intersecting the rear wall of one of the vertical slots below the inwardly extending slot, and continuous loops formed of a bendable strand of material whereby a portion of said loops may be expanded, adapted to be inserted through the vertical slots and acting to lock the fence wire within each of the seats, said loops being substantially elliptical in form. 25

In testimony whereof I hereunto affix my signature in the presence of two witnesses.

JAMES W. BEST.
